PUMP DRIVING MECHANISM

Alexander Quayle, Dallas, Tex., assignor to United States Steel Corporation, a corporation of New Jersey

Application April 7, 1953, Serial No. 347,339

7 Claims. (Cl. 74—665)

This invention relates to improvements in driving mechanisms for pumps in well drilling installations.

This application is a continuation-in-part of my earlier copending application Serial No. 149,765, filed March 15, 1950.

Larger well drilling installations commonly include two or more engines and a compounding unit which transmits power from these engines to the hoist and the pumps and sometimes to the rotary. The compounding unit enables any engine or combination of engines to drive any of these instrumentalities. In previous installations with which I am familiar, the pumps have been connected to the compounding unit either without variable speed transmissions or else the unit has included permanent variable speed transmissions to which the pumps are connected, as shown for example in Spalding Patent No. 2,488,069. These arrangements have the disadvantages that the two types of installations require compounding units which are constructed differently, and that one type cannot be converted to the other.

An object of the present invention is to provide improved compounding units that have demountable variable speed transmissions for driving the pumps, thereby enabling such a unit to operate as a single speed apparatus for driving the pumps on removal of the variable speed transmission.

A further object of the invention is to provide improved compounding units which enable units of identical construction to drive the pumps either as a single speed apparatus or via a variable speed transmission.

A further object of the invention is to provide improved variable speed transmissions for connecting a compounding unit and pumps and being removable so that the pumps can be connected to the compounding unit directly.

In accomplishing these and other objects of the invention, I have provided improved details of structure, preferred forms of which are shown in the accompanying drawings, in which:

Figure 1 is a top plan view of a compounding unit, engines, and pumps in which the unit is equipped with variable speed transmission according to one embodiment of the present invention;

Figure 2 is a vertical sectional view taken substantially on line II—II of Figure 1;

Figure 3 is a side elevational view of a variable speed transmission of modified construction;

Figure 4 is a top plan view of the transmission shown in Figure 3;

Figures 5 and 6 are side elevational views of variable speed transmissions of other modified constructions; and

Figure 7 is a top plan view of the unit with the variable speed transmissions removed and driving the pump as a single speed apparatus.

Figures 1 and 2 show a compounding unit 10 which, apart from the variable speed transmission feature, can be of any standard construction. Three engines 12, 13 and 14 are connected to the unit, which has shaft exten-

2

sions 15, 16 and 17 aligned with these respective engines. Shaft extension 15 has a power output means 18 for driving the hoist, not shown. The unit also drives two pumps 19 and 20. The unit has the usual clutches for engaging or disengaging the engines and the driven instrumentalities and also the usual mechanism for interconnecting the shaft extensions. In this instance the engines, compounding unit, and pumps are mounted on skids which enable the installation to be assembled or dismantled readily. The compounding unit skid is shown at 21 and rests on an elevated framework 22. The pump skids are shown at 23 and 24.

In accordance with the embodiment of the invention shown in Figures 1 and 2, a demountable variable speed transmission 25 is removably bolted to skid 21 and has power input means detachably coupled to shaft extension 16. The transmission has a power take-off 26, which in this instance extends outwardly away from the engines 12, 13 and 14. Flexible belts 27 connect said power take-off with a drive sheave 28 on pump 19. A separate demountable variable speed transmission 29 is removably bolted to skid 21 alongside transmission 25 and has power input means detachably coupled to shaft extension 17. This latter transmission has a power take-off 30, which in this instance extends in the opposite direction from the power take-off 26 inwardly toward the engines. Flexible belts 31 connect said latter power take-off with a drive sheave 32 on pump 20. The variable speed transmissions 25 and 29 can embody any standard mechanism which is capable of furnishing at least two forward speed ratios, and preferably are of like construction except that their power take-offs extend from opposite sides.

Figures 3 and 4 show a modification in which the variable speed transmissions have their own skids 33 and 34 which in turn rest on the compounding unit skid 21. Otherwise these transmissions are similar to the transmissions of the embodiment shown in Figures 1 and 2.

Figure 5 shows another modification in which both variable speed transmissions are carried in a common housing 35 which is removably bolted to the compounding unit skid 21, the same as the individual transmission housings shown in Figures 1 and 2.

Figure 6 shows another modification in which both variable speed transmissions are carried in a common housing 36 and in which the housing has its own skid 37. This skid rests on the compounding unit skid 21, the same as the individual transmission skids in Figures 3 and 4.

Figure 7 shows my improved compounding unit with the variable speed transmissions removed and operating as a single speed apparatus. Removal of these transmissions leaves the shaft extensions 16 and 17, to which they are otherwise coupled, accessible for connection with the pumps 19 and 20 to enable the unit to operate as a single speed apparatus in driving these pumps. The connection illustrated includes a pair of base plates A and B detachably mounted on the compounding unit skid, aligned bearings 38 and 39 carried by base plate A, aligned bearings 40 and 41 carried by base plate B, a stub shaft 42 which is rotatably mounted in the first two bearings and detachably coupled to the shaft extension 16, and a stub shaft 43 which is rotatably mounted in the last two bearings and detachably coupled to the shaft extension 17.

Stub shafts 42 and 43 carry power take-offs 44 and 45 respectively. Belts 46 and 47 connect these power take-offs with the drive sheaves of the two pumps. Base plate A, bearings 38 and 39 and shaft 42 are constructed as a unitary assembly which bolts to the skid 21 in the same bolt holes as the two speed transmission 25, thus facilitating a changeover from single speed to variable speed or vice versa. Similarly base plate B, bearings 40 and 41 and shaft 43 are constructed as a unit. Also it is apparent that with the embodiments of Figures 1 to 4, one of the

pumps can be driven via a variable speed transmission and the other via a stub shaft, if such an arrangement is desired.

During the drilling of a well with an assembly like that shown in Figure 7, it may become desirable to introduce one or more variable speed transmissions to furnish greater flexibility in the operation of the pumps to meet conditions not anticipated when the well was started. The unit assemblies enable such a change to be made with a minimum of delay. Flexibility in manufacture also results, since with one design of skid it is possible to furnish one or two single speed pump drives, one or two variable speed pump drives, or one of each with the variable speed at either location. Any of these arrangements may be required to meet special operating conditions. These changes can be made without expensive and time consuming machining or welding on the main assembly.

While I have shown only certain preferred embodiments of the invention, it is apparent that modifications may arise. Therefore, I do not wish to be limited to the disclosure set forth but only by the scope of the appended claims.

I claim:

1. A compounding unit comprising a supporting base, a plurality of shaft extensions rotatably supported above said base and adapted to be connected to engines to be driven thereby, power transmission mechanism interconnecting said shaft extensions, a pair of variable speed transmissions each constructed as a removable unit having power input means and power take-off means, means removably mounting said variable speed transmissions on said base, and means detachably coupling the power input means of said variable speed transmissions to two of said shaft extensions, the power take-off means of said variable speed transmissions extending in opposite directions and being adapted to be connected to a pair of pumps for driving the latter.

2. A unit as defined in claim 1 wherein removal of said variable speed transmissions from said base leaves the two shafts to which they are otherwise coupled accessible for connection with pumps to enable the compounding unit to operate as part of a single speed apparatus for driving the pumps.

3. A well drilling installation comprising a plurality of engines, a compounding unit, and a pair of pumps, said compounding unit including a supporting base, a plurality of spaced parallel shaft extensions rotatably supported above said base and each connected at its inner end to a different one of said engines, power transmission mechanism interconnecting said shaft extensions, a pair of variable speed transmissions each having power input means and power take-off means, means removably mounting said variable speed transmissions on said base adjacent the outer ends of two of said shaft extensions, means detachably coupling the outer ends of these shaft extensions to the power input means of said variable speed transmissions, the power take-off means of one of said variable speed transmissions extending outwardly away from the engines and that of the other extending in the opposite direction back toward the engines, and means connecting each of said power take-off means with a different one of said pumps for driving the latter.

4. An installation as defined in claim 3 in which the two variable speed transmissions have two individual housings removably mounted on said base.

5. An installation as defined in claim 3 in which the two variable speed transmissions have one common housing removably mounted on said base.

6. A well drilling installation comprising a plurality of engines, a compounding unit, and a pump, said compounding unit including a supporting base, a plurality of spaced parallel shaft extensions rotatably supported above said base and each connected at its inner end to a different one of said engines, power transmission mechanism interconnecting said shaft extensions, a variable speed transmission having power input means and power take-off means, means removably mounting said variable speed transmission on said base adjacent the outer end of one of said shaft extensions, means detachably coupling the outer end of this shaft extension to the power input means of said variable speed transmission, and means connecting the power take-off means of said variable speed transmission with said pump for driving the latter, removal of said variable speed transmission leaving the outer end of the shaft extension to which it is otherwise coupled accessible for connection with said pump to enable said unit to operate as part of a single speed apparatus for driving said pump.

7. A well drilling installation comprising a plurality of engines, a compounding unit, and a pair of pumps, said compounding unit including a supporting base, a plurality of spaced parallel shaft extensions rotatably supported above said base and each connected at its inner end to a different one of said engines, power transmission mechanism interconnecting said shaft extensions, a pair of variable speed transmissions each having power input means and power take-off means, means removably mounting said variable speed transmissions on said base adjacent the outer ends of two of said shaft extensions, means detachably coupling the outer ends of these shaft extensions to the power input means of said variable speed transmissions, the power take-off means of one of said variable speed transmissions extending outwardly away from the engines and that of the other extending in the opposite direction back toward the engines, and means connecting each of said power take-off means with a different one of said pumps for driving the latter, removal of said variable speed transmissions leaving the outer ends of the two shaft extensions to which they are otherwise coupled accessible for connection with said pumps to enable said unit to operate as part of a single speed apparatus for driving said pumps whereby said unit can drive said pumps as a single speed apparatus on removal of said variable speed transmissions.
